Application March 22, 1957, Serial No. 647,774

7 Claims. (Cl. 188—78)

This invention relates to vehicle brake mechanism and particularly to return spring attachment arrangements for internally expanding brakes.

In its preferred embodiment the invention will be described as specifically applied to a brake assembly wherein dual web pivoted brake shoes are oppositely urged to brake retracted position by a return spring interconnecting the respective shoe webs. Prior to the invention it was conventional to interconnect a corresponding opposed web of such dual web shoes by a single spring such as disclosed in Super Patent No. 2,568,777, issued September 25, 1951. However difficulties in assembly and operation were encountered due to the unbalance of spring forces and the resultant tendency of the shoes to tilt laterally with respect to their support. This resulted in uneven wear at the pivot anchor pins for the brake shoes, and increased the need for frequent adjustment besides reducing the overall lining life.

The present invention corrects this difficulty by providing a return spring and dual web brake shoe association wherein the spring forces tending to oppositely pivot the shoes exert essentially no lateral tilting forces on the shoes. This is done by providing a special centered bridge between the webs on the respective shoes for opposite end attachment to the return spring.

It is the major object of the invention to provide a novel dual web pivoted shoe brake assembly wherein the shoe webs have balanced connection with a single return spring in such manner that the spring has essentially no tendency to tilt the shoes laterally of their pivot axes.

A further object of the invention is to provide a novel brake assembly wherein a special return spring connecting member is mounted to bridge the dual webs of each brake shoe.

It is a further object of the invention to provide in a dual web brake shoe a centered bridge member formed for attachment of one end of a return spring and mounted between the webs so that it is readily installed or intentionally removed but is not accidentally detached from operative position.

A further object of the invention is to provide a novel integral return spring attachment member for mounting between the webs of a dual web brake shoe.

Further objects of the invention will appear as the description proceeds in connection with the appended claims and the annexed drawings wherein:

Figure 1 is a side elevation showing the general brake assembly embodying the invention and showing the return spring connection;

Figure 2 is a fragmentary view mainly in section on

2

line 2—2 of Figure 1 and showing the return spring attachment member in operative position bridging the dual shoe webs;

Figure 3 is an enlarged side elevation of the bridge member showing details of structure;

Figure 4 is an end elevation of the bridge member of Figure 3; and

Figure 5 is a section on line 5—5 of Figure 3.

In the illustrated embodiment of the invention dual web brake shoe assemblies 11 are pivoted at adjacent ends on parallel axis anchor pins at 12 carried by a rigid suitable backing plate or other support. The opposite ends of the shoe assemblies rotatably carry cam follower rollers 13 urged into engagement with a rotatable actuating cam 14 by a single return spring 15 as will appear. The shoes 11 are essentially the same although oppositely pivoted so that spring 15 normally urges them toward brake retracted position.

Each shoe assembly 11 comprises an arcuate platform 16 upon which is cemented or riveted one or more blocks 17 of friction liner material, and spaced parallel flat co-extensive webs 18 and 19 are rigid with the concave side of platform 16. Platform 16 and webs 18 and 19 are preferably fabricated from sheet metal sections suitably formed and welded together, and webs 18 and 19 are parallel to the side edges of platform 16 and equally spaced therefrom.

At the pivot ends each shoe web 18 and 19 is formed with similar anchor pin mounting apertures 21 in coaxial alignment. At the opposite ends each shoe web 18 and 19 is formed with similar open end journals 22 in coaxial alignment, and these journals rotatably support the oppositely projecting shaft sections 23 of cam follower rollers 13.

Near the cam follower end of each shoe assembly the webs 18 and 19 are formed with coaxial circular apertures 24 and 25 of the same size, and a bridge member 26 is mounted with opposite ends disposed in these apertures.

Bridge member 26 is integrally formed from a length 40 of round wire stock and comprises similar end sections 27 and 28 in axial alignment, and an offset intermediate section 29. Preferably member 26 is formed from a suitable length of $1/4$ " diameter round spring steel wire that will retain a given shape. As will appear bridge member 26 is rigid enough not to appreciably deflect during normal operation of the brake assembly but it is sufficiently longitudinally flexible to slightly deform and spring back to shape during insertion and removal. Intermediate section 29 is connected to the end sections by inclined portions 31 and 32, and as shown in Figure 4 the entire bridge member is symmetrical about a plane containing the axes of the end and intermediate sections.

At the juncture of the inclined portions of the bridge with the associated end sections relatively thin flat ribs 33 and 34 are provided, these being preferably formed by a compressive action of the metal wire at those places to squeeze the metal outward into flat rib shape extending substantially radially of the wire and in the opposite direction diametrically from the offset intermediate section 29.

At the opposite ends of the bridge member are formed inclined surfaces 35 and 36, these being inclined about 30° to the common axis of the end sections and diverging

in the direction of the offset section 29. Surfaces 35 and 36 lie in planes that intersect at 90°.

The intermediate section 29 is formed with a central lateral groove or depression 37 which is preferably formed by bending the wire at that point. In practice the wire is sinusously bent in the intermediate section so that depression 37 is flanked by raised formations 38 and 39. The adjacent end of spring 15 is formed into a hook at 41 as shown in Figure 1 to fit over into depression 37 between the raised formations 38 and 39 that keep the hook from being laterally displaced toward either web in the assembly.

As shown in Figure 4 the intermediate section 29 is displaced into substantially parallel lateral offset relation to the end sections by a distance approximately equal to the diameter of the wire. As shown in Figure 3 the bridge member 26 has a maximum transverse dimension A measured between parallel planes containing the outer tips of 33 and 34 and the opposite side of the intermediate section 29, and this dimension A is greater than the diameter B of apertures 24 and 25 so that the bridge member cannot pass straight through the dual webs.

After being formed to the shape of Figure 3 the bridge member 26 is heat treated to relieve strains induced by forming. The beveled ends 35 and 36 merely facilitate entry of the end sections into the web apertures.

The bridge member 26 may be inserted by hand either end first from either side of the webs, and Figure 3 shows in dotted lines insertion from the right into the limit position to which it may usually be pushed manually. It will be noted that at this point the inclined cam or wedge surface 42 has encountered the edge of aperture 24, and the opposite end section 28 has entered aperture 25. Then axial force is applied to member 26, as by tapping it with a hammer, and the inherent springiness of the bridge member resiliently flexes it temporarily and enables surface 42 to cam past aperture 25. The same action takes place when inclined cam or wedge surface 43 of rib 33 encounters the edge of aperture 25, and thus eventually the bridge member 26 is driven like a nail into the webs so that the end sections 27 and 28 are disposed in the apertures 24 and 25 respectively, and the intermediate section 29 is disposed in the space between the webs 18 and 19. The cylindrical surfaces of end sections 27 and 28 will be effectively journaled on the circular bearing edge areas of apertures 24 and 25, and with the bridge members 26 inserted into both brake shoes the return spring may now be attached. This is done by pivotally hooking the hook 41 over the depressions 37 in the bridge members 26 of the opposed shoes. Since the spring 15 is thus under tension the bridge members 26 will be pulled to the sides of the web apertures opposite the platform 16, as shown in Figure 1. This is facilitated by the rocking sliding bearing engagement of the end sections of the bridge members in the web apertures, and as shown in Figure 2 it locates each bridge member 26 in such position in the brake assembly that the offset section 29 is offset with respect to the web apertures and cannot be laterally displaced to any appreciable extent.

The bridge member 26 is symmetrical and has these cam or wedge surfaces 42, 43 located for insertion in either direction as shown. In practice the surfaces 42, 43 are usually $\frac{1}{4}$ " radius surfaces on the ribs.

Since the depressions 37 are located centrally of the bridge members and therefore centrally of the brake shoes in the assembly the force exerted by spring 15 tending to oppositely rock the shoes 11 about anchor pins 12 is effectively exerted in a plane about perpendicular to the axes of anchor pins 12 and therefore there is little or no tendency of the brake shoes 11 to tilt due to spring tension. The bridge members 26 automatically center the return spring between the brake shoes 11.

To remove the bridge member 26 from the full line

position of Figure 3 after uncoupling spring 15, a punch may be employed to drive one end axially through its associated aperture, and then it can be removed by hand. In this action the bridge member resiliently flexes temporarily when driven by the punch. It will be seen that the bridge member 26 may be assembled with its shoe for inventory and shipping and there will be no danger of its accidentally dropping out.

The invention may be embodied in other specific forms without departing from the spirit or essential characteristics thereof. The present embodiment is therefore to be considered in all respects as illustrative and not restrictive, the scope of the invention being indicated by the appended claims rather than by the foregoing description, and all changes which come within the meaning and range of equivalency of the claims are therefore intended to be embraced therein.

What is claimed and desired to be secured by United States Letters Patent is:

1. An internally expanding brake comprising two brake shoe assemblies pivoted at adjacent ends and operatively connected to an actuator at their other ends, each of said shoe assemblies having an axially spaced pair of side by side longitudinal webs substantially centrally disposed of the shoe assembly and the webs of each shoe assembly being formed with aligned apertures, a return spring attachment member bridging each pair of webs and having its opposite ends freely mounted in said apertures and an intermediate section offset laterally from said ends in the space between said webs, and a return spring connected at opposite ends substantially centrally of said intermediate sections of said members, said return spring being under tension in the assembly and normally tending to rock said shoe assemblies toward each other, and each said attachment member having a transverse dimension measured between parallel planes containing the opposite outer sides of said offset section and said ends greater than the maximum transverse dimension of at least one of its associated web apertures, and each said member being sufficiently flexible and resilient to deflect during insertion or removal with respect to said web apertures and spring back to original condition.

2. An internally expanding brake comprising two brake shoe assemblies pivoted at adjacent ends and operatively connected to an actuator at their other ends, each of said shoe assemblies having a pair of side by side axially spaced longitudinal webs substantially centrally disposed of the shoe assembly and the webs of each pair being formed with apertures that provide aligned arcuate bearing surfaces, a return spring attachment member bridging each pair of webs having opposite aligned end sections rockably mounted on said bearing surfaces and an intermediate section offset laterally from said end sections disposed between said webs, and a single return spring connected at opposite ends substantially centrally of said intermediate section, said return spring being under tension in the assembly and normally tending to rock said shoe assemblies toward each other.

3. An integral return spring attachment bridge for a dual web brake shoe comprising axially spaced and aligned similar end sections, an intermediate section laterally offset to said end sections, means defining inclined cam surfaces on said end sections adjacent their juncture with said offset intermediate section and projecting from said end sections in the opposite direction from said offset section, and a spring attachment station located substantially centrally of said intermediate section.

4. In the return spring attachment bridge defined in claim 3, said return spring attachment station being a surface depression in said intermediate section.

5. An integral return spring attachment bridge member made from a single length of round wire stock comprising similar coaxial end sections, a substantially parallel inter-

mediate section laterally offset from said end sections and having oppositely inclined portions connecting opposite ends of the intermediate section with the end sections longitudinally aligned ribs formed on said end sections to project in the direction opposite from said offset section, and a spring end mounting formation substantially centrally of said intermediate section.

6. In the bridge member defined in claim 5, said formation being a surface depression in said intermediate section flanked by relatively raised regions.

7. The bridge member defined in claim 5, said member being symmetrical about a plane containing said ribs and the axes of the end and intermediate sections,

5
6
and being symmetrical on both sides of said spring end mounting formation.
